UNITED STATES PATENT OFFICE

2,519,947

FEED MECHANISM FOR MACHINE GUNS

Andrew K. Watt, Lansing, Mich., assignor to General Motors Corporation, Detroit, Mich., a corporation of Delaware

Application September 14, 1945, Serial No. 616,331

4 Claims. (Cl. 89—33)

1

The present invention relates to an improvement in a feed mechanism particularly adapted for use with or as a part of an automatic firearm of the character disclosed in Patents Nos. 1,525,065, 1,525,066, and 1,692,328 issued in the name of John M. Browning.

With feed mechanisms of the type disclosed in the aforementioned patents, considerable difficulty has been experienced due to over-feeding of the belt of ammunition. Ammunition for such guns is supplied in the form of a belt of cartridges formed by the so-called disintegrating type of belt links. In such a gun the cartridges are fed transversely into a feed box located on top of the gun. Lateral movement is imparted to the belt of cartridges by the feed slide to bring the foremost cartridge underneath a stripper cam which strips the cartridge downwardly out of the belt link. However, due to the high speed at which the feeding mechanism operates, the remainder of the belt of cartridges, through inertia or other causes, occasionally continues to move through the feed box so that a second cartridge is stripped or at least partially stripped from the link. This condition naturally produces a jam in the feed box and interrupts the firing of the gun. A similar difficulty may be encountered in manually feeding cartridges into the gun by operation of a suitable feed lever.

It is therefore an object of this invention to provide a device which may be readily attached to a gun similar to those described in the aforementioned patents which will prevent over-feeding of a belt or strip of cartridges.

The specific nature of the invention as well as other objects and advantages thereof will clearly appear from a description of a preferred embodiment as shown in the accompanying drawings in which:

Fig. 1 is a side elevational view of the cartridge entering side of a feed box for an automatic firearm of the type disclosed in the aforementioned patents to Browning;

Fig. 2 is an enlarged side elevational view of the operating elements of Fig. 1 embodying this invention. For purposes of clarity the surrounding components of the feed box of Fig. 1 which do not relate to this invention have not been shown in Fig. 2;

Fig. 3 is a top view of the elements shown in Fig. 2;

Fig. 4 is an enlarged partial sectional view of Fig. 1 taken along the plane 4—4 thereof; and

Fig. 5 is an isometric view of the end portion

2

of the feed slide showing the cam track formed thereon.

In Fig. 1 there is shown a machine gun comprising a casing or receiver portion 2 and a feed box 4 mounted on top of the receiver 2. In the modification disclosed, the cartridge entering side of the feed box is shown on the right hand side of the gun but it should be understood that the invention may be applied to either right hand or left hand feeding mechanisms. A sheet metal chute member 6 is secured to the side of feed box 4 in alignment with a suitable slot 7 therein to define a feed channel for receiving a belt of cartridges 8 which are secured together by disintegrating links 9. The links 9 are preferably of the type described in Patent No. 2,392,280, dated January 1, 1946, in the name of Harold T. Youngren and assigned to the assignee of this application. Such links are provided with a pair of front and rear stripping tabs 10 which project from the body of the link 9 in a direction parallel to the axis of the cartridges 8 and are somewhat raised above the adjacent portion of the cartridge.

A pair of feed tracks 11 are riveted to the top surface of chute member 6 in spaced relation overlying the links 9 on the cartridges 8. Feed tracks 11 respectively engage the stripping tabs 10 of the links 9 to support and guide the links into the feed box. Tracks 11 communicate with similar tracks 12 provided in the interior of feed box 4 and tracks 12 carry the links to the stripping cams 15 as is more fully described in the aforementioned patents.

Within the feed box 4 and in overlying relationship to the path of the belt of cartridges, there is provided a feed slide 13 which is mounted in the feed box 4 for transverse reciprocating movement and is actuated either by firing of the gun or by a manual lever (not shown) to reciprocate back and forth across the feed box and by means of conventional feed pawls 16 to successively advance the belt of cartridges into the feed box in position for loading into the chamber of the barrel. The drawings fully show that portion of the feed mechanism to which this invention particularly relates. For details of the machine gun which are not herein fully shown or described, reference may be made to the aforementioned Browning patents.

Adjacent the cartridge entering wall of feed box 4, in accordance with this invention, a belt stop pawl bracket 20 is mounted. The belt stop pawl bracket 20 comprises a generally rectangular member which is secured to the side wall of feed box 4 by bolts 21. It is provided with a

recess 22 in its side adjacent feed slide 13 in which a belt stop pawl 23 is pivotally mounted on a pin 24. The belt stop pawl 23 comprises an L-shaped member which is pivotally mounted in horizontal pin 24 at the intersection of its vertical arm 25 and horizontal arm 26. The arm 25 projects upwardly and extends through a suitable slot in the top of feed chute 6. The extreme end portion of arm 25 may be provided with serrations 27 to facilitate the use of this arm as an operating handle for the pawl 23. The other arm 26 of the pawl 23 normally lies in a substantially horizontal position and its extreme end 28 lies adjacent the side of feed slide 13. A depending locking projection 32 is provided on the end of arm 26 of pawl 23 which is the so-called normal position of the pawl 23 lies on the top of the rear feed track 11 and thus lies in the path of the rear stripping tab 10 of the belt links. The pawl 23 is a spring-biased to its normal position by means of a plunger 40 and spring 41 which are mounted in a suitable recess 42 provided in bracket 20.

The arm 26 of feed pawl 23 is provided with a hollow cylindrical recess 29 in which is mounted a plunger 30, which is biased outwardly by a spring 31 and retained in the recess 29 by a transverse pin 33 which cooperates with a flat 34 on plunger 30 to permit limited axial movement of plunger 30 relative to recess 29. The projecting end of plunger 30 engages a cam track provided on the side of feed slide 13. Said cam track comprises a vertical ramp surface 37, a transversely angular surface 38, a longitudinally vertical surface 35 and a dwell 36. Vertical ramp surface 37 is suitably shaped so that when feed slide 13 is moving in a feeding direction, the plunger 30 is cammed vertically upwardly and hence the entire pawl 23 is pivoted in a counterclockwise direction as indicated by the dotted line position shown in Fig. 2, thus raising locking projection 32 out of the path of feeding movement of the rear stripping tab 10 of the belt links. At the end of the feeding movement of slide 13, or when the leading cartridge has been stripped out of its link by the stripper cams 15, the right hand end portion of feed slide 13 passes out from under plunger 30 of stop pawl 23, permitting stop pawl 23 to pivot downwardly under the bias of spring pressed plunger 40 to its normal position wherein the locking projection 32 is disposed in front of the stripping tab 10 of the next cartridge. Thus further movement of the belt of cartridges into the feed box due to inertia or other forces is prevented.

As feed slide 13 is returned to its ready-to-feed position by conventional mechanism, the stop pawl 23 remains in its normal position. However a transversely angular surface 38 on the end of feed slide 13 forces plunger 30 back to permit the feed slide 13 to pass stop pawl 23. When feed slide 13 reaches the end of its return movement, plunger 30 snaps forward into dwell 36 and the mechanism is in condition for the next feeding cycle.

It is therefore obvious that a device embodying this invention eliminates the possibility of a feeding jam due to over-travel of the belt of cartridges. At the same time, due to the action of the cam track on the feed slide 13, the stop pawl 23 offers no obstruction to the normal feeding movement of the belt of cartridges. It should also be noted that the pawl 23 acts as a stop to prevent an inadvertent removal of the belt of

cartridges from the gun by movement of the belt in a counter-feeding direction. When it is desired to remove a belt of cartridges such can be readily done by manually operating handle portion 25 of stop pawl 23.

I claim:

1. In a machine gun having a feedway arranged to receive a belt of linked cartridges, and a feed slide mounted for reciprocating movement along the feedway and constructed to successively advance the cartridges into the gun, the improvement comprising in combination, a pawl pivotally mounted in the gun adjacent the feedway, said pawl having a projection thereon movable into the path of movement of the links of the cartridge belt, a cam track on the feed slide, a spring pressed plunger extending from said pawl and having the free end thereof engageable with said cam track, said cam track comprising a ramp surface for camming said plunger and thereby said pawl during a portion of the feeding movement of the slide to lift said projection from in front of the links, and an angular cam surface at the front corner of the feed slide for camming said plunger rearwardly against the bias of its spring to permit the return movement of the feed slide.

2. The combination defined in claim 1 and a handle portion on said pawl projecting out of the gun whereby said pawl may be manually moved out of the path of the belt of cartridges.

3. In a machine gun, in combination, a feed box defining a feedway arranged to receive a linked belt of cartridges therein having a stripping tab on each of the links, a feed slide mounted for reciprocating movement along said feedway and constructed and arranged to successively advance the belt of cartridges into the gun, a pawl pivotally mounted on the gun adjacent said feedway, said pawl having a projection depending therefrom, resilient means biasing said pawl and thereby said projection in front of the stripping tabs to limit the movement of the links, a cam track in the side of said feed slide, a spring pressed plunger extending from said pawl and having the free end thereof normally engageable with said cam track, said cam track comprising a ramp surface for camming said pawl upwardly during feeding, said projection being thereby lifted from in front of the stripping tabs on the links and then released to said former tab-engaging position as said feed slide reaches the end of its feeding movement, and an angular cam surface at the front corner of said feed slide and adjacent said ramp surface for camming said plunger rearwardly to permit the return movement of said feed slide.

4. In a machine gun, in combination, a feed box defining a feedway arranged to receive a linked belt of cartridges therein having a stripping tab on each of the links, a feed slide mounted for reciprocating movement along said feedway and constructed to successively advance the belt of cartridges into the gun, a pawl pivotally mounted on the gun adjacent said feedway, said pawl having a projection depending therefrom, resilient means biasing said pawl and thereby said projection in front of the stripping tabs to limit the movement of the links, a cam track on the side of said feed slide, a spring pressed plunger extending from said pawl and having the free end thereof normally engageable with said cam track, said cam track comprising a ramp surface for camming said pawl upwardly during feeding, said projection being

thereby lifted from in front of the stripping tabs on the links and then released to said former tab-engaging position as said feed slide reaches the end of its feeding movement, an angular surface at the front corner of said feed slide for camming said plunger rearwardly during the first portion of the return movement of said feed slide, a vertical surface for maintaining said plunger rearwardly during the middle portion of said return movement, and a dwell at the end of said cam track to permit re-engagement of said plunger therewith for the remainder of the return movement of said feed slide.
